UNITED STATES PATENT OFFICE

157,709

EMBORESSED METAL SHEET

Richard S. Smith, Buffalo, N. Y.

Application April 16, 1949, Serial No. 2,040

Term of patent 14 years

(Cl. D54—2)

To all whom it may concern:

Be it known that I, Richard S. Smith, a citizen of the United States and resident of Buffalo, New York, have invented a new, original, and ornamental Design for an Embossed Metal Sheet, of which the following is a specification, reference being had to the accompanying drawing, forming part thereof.

In the drawing:

Fig. 1 is a view looking directly at the face of an embossed metal sheet, showing my new design;

Fig. 2 is a cross-sectional view on the line 2—2 of Fig. 1; and

Fig. 3 is a cross-sectional view on the line 3—3 of Fig. 1.

The background ornamentation has been partly omitted from Fig. 1 for convenience in illustration.

I claim:

The ornamental design for an embossed metal sheet, as shown and described.

RICHARD S. SMITH.
